GLASSWARE-FORMING APPARATUS

Edward Danner, Newark, Ohio

Application February 24, 1941, Serial No. 380,179

18 Claims. (Cl. 49—17.1)

One of the objects of the present invention is to provide an efficient glass tube forming apparatus, wherein the molten glass is intermixed to assure uniformity of constituency and, consequently, uniformity of viscosity when at any uniform temperature to which the glass is raised. It then becomes dependable as to its fluidity and its corresponding reactive formation in producing the ware. The invention, particularly, resides in the manipulation of the glass and the shaping of the glassware by defined apparatus.

The invention, also, consists in an adjustable heat-insulating shell surrounding the glass at its ware-forming point for not only cooperatively producing zonal confinement of the heat about the glass during its ware formation, but, also, to vary the escape of heat and induce the flow of a limited and controllable quantity rate of temperature-reducing air to control the viscosity of the glass, as it moves over the shaping element.

The invention, also, provides an adjustable heat-distributing shield or deflector for varying the viscosity of the glass to produce varying rate of flow of portions of the glass on the forming element and as it leaves the forming element to vary not only the structural characteristics of the glass body, but, also, the dimensional characteristics of the ware.

The invention, also, provides an annular damper located at the top of the shell for adjustably covering an opening intermediate the shell and the bottom of a molten glass container, such as a glass-delivering trough, or a forebay or forehearth, to regulate the draft within the shell and the escape of the heated gas and the products of combustion and vary the intake of air within the shell and about the glass and, thus, control the viscosity of the glass.

The invention, also, provides a ware-forming element having glass-distributing parts to produce a uniform glass quantity rate of formation into ware and, thus, desired definite ware quality and definite variations in wall thickness, according to the variations in shape or number of the glass-distributing parts. The invention, also, provides a means for readily assembling the distributing parts to enable variation of their effectiveness as to the glass quantity rate that flows from the ware-forming element.

The invention, also, provides a molten glass conduit having a glass-shaping element at its lower end and a blow pipe within the glass conduit and means for directing air transversely through the flowing glass to the blow pipe.

The invention, also, provides a surface glass

heating means and a glass-shaping element supported in the outlet of a molten-glass conduit and connected by interengaging blocks with the lower end of the conduit and the lower end of a blow pipe located within the element for supporting the shaping element and the blow pipe and preventing surface heating of more than a limited area of the surface glass.

The invention, also, provides a glass-shaping element having a plurality of substantially uniformly spaced, relatively thin parts located in a stream of molten glass or in an outlet through which molten glass moves for producing a constant, relatively high quantity rate of discharge of molten glass. The invention, also, provides a means for securing the lower terminals of the parts at desired points relative to each other and with respect to the stream flow to produce desired dimensional characteristics of the ware formed by the shaping element.

The invention, also, consists in providing a glass-shaping element having one or more glass-distributing parts for producing an increased quantity rate of discharge of molten glass from a chamber and a glass-directing body axially disposed with reference to the parts and having a surface for producing in-gathering of the glass as it is discharged from the parts or a wider distribution of the glass than the normal flow from the parts and, thus, deviation inwardly or outwardly with respect to the axis of the normal flow.

The invention, also, provides a readily replaceable tip part of a glass-shaping element to cause deviation from the normal downward movement of the glass as it reaches a point of free fall and, thus, vary the dimensional characteristics of the glass.

The invention consists in other features and advantages which will appear from the following description and upon examination of the drawings. Structures containing the invention may partake of different forms and still embody the invention. To illustrate a practical application of the invention, I have selected a glassware-forming apparatus as an example of the various structures and details thereof that contain the invention and shall describe the selected structure hereinafter, it being understood that variations may be made and that certain features of my invention may be used to advantage without use of other features of the invention and without departing from the spirit of the invention, as presented in the claims. The particular struc-

ture selected is shown in the accompanying drawings and described hereinafter.

Fig. 1 is a front view of the forebay or forehearth and a broken outline view of a melting tank. Fig. 2 is a view of a vertical section, taken on the plane of the line 2—2 and looking in the direction of the arrows, indicated in Fig. 1. Fig. 3 is a view of a horizontal section, taken on the plane of the line 3—3, indicated in Fig. 2. Fig. 4 is a view of a section of the gate intermediate the melting tank and the forebay for controlling the flow of molten glass to the forebay. Fig. 5 is a view of a vertical section of a glass-shaping element, in mandrel form, its enclosing shell, and the contiguous coacting parts in the forebay, also taken on the plane of the line 2—2, indicated in Fig. 1. Fig. 6 is a view of a section, taken on the horizontal planes of the broken line 6—6, indicated in Fig. 5, and illustrates the flame-shield elevator for modifying the zonal temperature range about the glass-shaping element. Fig. 7 shows a view of a section, taken on the plane of the line 7—7, indicated in Fig. 5, showing the damper ring and means for operating it. Fig. 8 illustrates a modified form of glass-shaping element, the heating burners, and the shield elevator for altering the zonal temperature produced by the burners. Fig. 8A is an enlarged sectional view of the shaping element and adjacent parts illustrated in Fig. 8. Fig. 9 is a perspective view of one of the molten glass-distributing parts of the glass-shaping element, shown in Fig. 8. Fig. 9A is a partial sectional view through the shell shown in Fig. 9. Fig. 10 is a view of a section of a third modified form of glass-shaping element. Fig. 11 illustrates a fourth modified form of a glass-shaping element and its enclosing shell. Fig. 12 illustrates one of the spacing and interlocking blocks for supporting the glass-shaping element and blow pipe, shown in Fig. 11. Fig. 13 illustrates an enlarged sectional view of the upper end part of the blow pipe, shown in Fig. 11. Fig. 14 illustrates a sectional view of a form of a glass-shaping element similar to that shown in Fig. 11. Fig. 15 illustrates a modified form of glass-shaping element having a replaceable tip or glass-delivery terminal. Fig. 16 illustrates a glass-shaping element having a replaceable tip, of still another form, to cause distribution of the glass over a circle having a larger area than is produced by the form shown in Fig. 15. Fig. 17 illustrates a perspective view of the tip shown in Fig. 16. Fig. 18 illustrates an enlarged view of a section of the engaging means for connecting the tip shown in either of the Figs. 15 and 16 with the body of the glass-shaping element, taken on the plane of the line 18—18, indicated in Fig. 19. Fig. 19 is a view of a section of the body of the shaping element, taken on the plane of the line 18—19, indicated in Fig. 15. Fig. 20 illustrates a modified form of a glass-shaping element, wherein a plurality of coaxial glass-distributing parts, in the form of shells, have flange or skirt parts that protrude well beyond the blow pipe terminal. Fig. 21 illustrates a form of glass-shaping element, similar to that shown in Fig. 20, wherein the flange parts, of the form of the glass-shaping element shown in Fig. 20, protrude below the terminus of the blow pipe at varying lengths and, particularly, to lengths that progressively increase from the outer of the parts to the inner of the parts and, thus, produce an inward draw of the glass to that discharged from the surfaces of the innermost of the parts. Fig.

22 illustrates a form of glass-shaping element, wherein a substantially semispherical-shaped refractory part may be removably connected to the central of the shell parts. Fig. 23 illustrates a perspective view of one of the shell-like parts shown in Fig. 22. Fig. 24 illustrates a broken view of sections of the substantially semispherical refractory part and the inner of the shell parts and shows a means for supporting the refractory body part.

In the form of construction shown in the figures, the melting tank 31 and its one or more forebays 32 are formed of refractory and insulating blocks of the usual type that are bonded by structural beams, rods, plates, and metal shells to form the supporting frame 34 of the apparatus. The batch materials are melted in one end of the tank and the melted glass is skimmed and the dross is retained by suitable floats and the clear glass is directed to the forebays, from which the glass flows or is drawn to form the glassware.

The glass is usually kept above a certain level and the lighter and more liquid surface glass, 25 that is subject more directly to the heat, is directed to the forebays and used while its fluidity renders it flowable and its viscosity renders it shapeable. Thus, the glass flows to the forebay 32 through a channel 35, wherein its 30 passage may be controlled by a gate 37, which may be raised by a rod 38 that extends through a part of the supporting frame and its height, with respect to the bottom of the trough or channel 35, adjustably positioned by the manually 35 rotatable nut 40.

The gate, preferably, seats against removable refractory slabs 41 that may be, if desired, grooved to receive the edge surfaces of the gate. The slabs are placed in grooves or side and bottom channels 40 46 formed in the sides and bottom of the channel 35 or passageway for the molten glass and separated from the surfaces of the channel 35 by sheets of asbestos 39. The side slabs 41 rest on the ends of the bottom slab 41 and are held in place by 45 dowel pins 42 that extend downward through parts 44 of the refractory wall of the tank that form the ends of the side grooves or channels 36. To enable removal of the slabs, they may be provided with holes 45, in which rods, or other instruments, may be inserted to draw the slabs from the grooves when the dowel pins have been removed. Thus, when, by erosion of parts of the slabs by the flow of the molten glass and leakage 50 at the gate, the slabs may be readily replaced by 55 new slabs and the gate used to completely close the channel 35.

The forebay 32 is cylindrical in form and its upper end is closed or covered by refractory blocks, one of which is provided with an opening 60 for receiving and adjustably supporting a blow pipe 47 extending through a refractory tube 48, which extends, with the pipe, through the molten glass to the glass-shaping element located below the forebay to protect the metal of the pipe. Compressed air is supplied to the blow pipe by a pipe 49.

The upper part of the forebay has a plurality 70 of refractory blocks, in which recesses 46, preferably, having curved surfaces substantially cylindrical or slightly conical, are formed to have axes that are located tangential to a circle, but slightly smaller than the curvature of the inside surface of the forebay. Fuel gas burners 48 are located 75 at the outer ends of the recesses for projecting

flames through the recesses into the forebay. The recesses coact directly to produce a whirling flame in the forebay at and over the surface of the glass. The burners are connected to a source of supply of fuel gas through pipes 53.

A refractory shell 50 is located below the level of the burners. This shell surrounds the inner end of the outlet 51 in the bottom of the forehearth through which the molten glass leaves the forehearth. This shell is preferably cylindrical and extends a short distance above the level of the glass in the forehearth. The upper end of the shell has a flange with a sloping lower surface adapted to cooperate with slidable blocks 54. These slidable blocks are positioned on the bottom surfaces of ports in the side wall which are closed by refractory plugs 52. The upper surface of each block slopes downwardly and is adapted to engage the sloping surface on a flange 55 on the shell 50 for cooperation therewith to raise or lower the one side of the shell.

A wall extends from the channel 35 and circularly along the wall of the forehearth. This wall is higher than the normal depth of the glass and forms a pot 56 for receiving the glass through the channel 35.

The glass is conducted from the forebay to a glass-shaping element located below the outlet 51. In the form shown in Figs. 2 and 5, the shaping element is supported on the lower end of the blow pipe 47 and, as the glass is distended by the glass-shaping element in the formation of the ware, it is sustained by the slight pressure produced by the air flow through the blow pipe 47. The blow pipe 47 has a refractory block 57. The block 57 has an outwardly extending shoulder 58 and the upper end of the shaping element 60 has an inwardly extending shoulder 61. The shaping element shown in Fig. 5 is in the form of a hollow mandrel having a tapered lower end and is supported on the refractory block 57 by small refractory spacing blocks 62 located intermediate the shoulders on the block 57 and the shaping element 60. The glass flows through the outlet 51 onto the upper ends of the block 57 and the shaping element 60 and over the inner and outer surfaces of the element 60 and its viscosity and its temperature controlled until it leaves the element. In this form of shaping element, the glass tends to form, by the air draft and heat, a skin of surface glass that is sometimes difficult to control. The glass skin alters the elasticity of the surface glass and, sometimes, produces gob-like collections and, at times, prevents uniformity of discharge at the lower end of the mandrel.

To regulate the viscosity of the glass and control its wall thickness as it is shaped by the shaping element, the glass-shaping element is surrounded by a heat-confining shell 64 formed of bonded refractory blocks. Burners 65 are located on a circular pipe 63 extending along the lower end edge of the shell. When forming cylindrical or circular ware, the shell is, preferably, cylindrical and has open ends. Preferably, the lower end of the shell has a conical or beveled edge surface to deflect the flames, produced by the burners, inwardly. The upper end of the shell is placed contiguous to the bottom of the forebay and the shell is located coaxial with the molten glass outlet 51 and with the shaping element 60. Thus, the glass, as it moves downward over the shaping element, is heated by the flames produced by the burners as confined and reflectively intensified by the shell.

The heat may be further intensified, or localized, by a shield 66 that may be adjustably supported by a frame 67 located below the burners and raised or lowered within the shell and, particularly, with respect to the shaping element 60 to produce zonal temperatures of more intense heat as may be desired. The shield 66 is, preferably, formed frustum and its shorter edge is located at the top and has a size and shape approximating that of the cross sectional area of the glass-shaping element, while its lower edge conforms in shape and approximates the size of the cross dimensions of the inner surface of the shell. The height of the frustum is, relative to its dimensions, short and, thus, the shield not only coacts to confine the heat about the element, but markedly reflects the heat of the burners and deflects the heated gases and exhaust products of combustion toward the glass-shaping element. Thus, the temperature about the shaping element, over which the glass moves, may be controlled to produce a desired viscosity to modify its rate of movement and its thickness of wall formation.

The shield 66 is supported by means of the rods 68 removably connectable to the Y-shaped frame 67. One of the arms of the frame 67 may be connected to a rack bar 70 that may be adjustably moved in the tube 71, by means of the pinion 72 and the crank 74 pivotally mounted in a housing connected to the lower end of the shell 64.

The shell 64 and the parts mounted thereon are supported by the rods 75 that are connected to parts of the forebay frame. The rods 75 may be provided with nuts 76 having crank handles 77 that may be rotated to raise or lower the upper end of the shell to or from the bottom wall of the forebay.

The effective area of the opening at the upper end of the shell 64 may be varied by the movement of the refractory ring damper 80 slidably supported on the upper end of the shell and movable toward and away from the bottom of the forebay. Preferably, the external diameter at the top of the shell is reduced to form a neck and the damper is formed of bonded curved refractory blocks and slidably fits the neck of the shell. The damper may be raised and lowered by a rotatable hand wheel and rod 81 that is connected, through sprocket wheels and sprocket chain 82, to the threaded rods 84 to rotate the rods 84. The rods 84 extend into threaded parts of the damper ring 80 and, when the rods 84 are rotated, they raise and lower the damper ring 80 and, thus, vary the effective area of the adjusted opening between the upper end of the shell and the bottom of the forebay.

The glass-shaping element 87, shown in Fig. 8, comprises a plurality of metal shells 88 and an outer refractory ring 90 supported on the end of the blow pipe 47 that extends through the outlet 51. The lower end of the blow pipe carries a sleeve 47' having a shoulder 47'' thereon. The innermost shell 88 is carried on the end of the blow pipe by short spacing blocks 91 which cooperate with the lower end of the blow pipe and with the shoulder 92 on the shell. The middle shell 88 is carried by the innermost shell 88 by means of interposed spacing blocks 91 which cooperate with the outer shoulder 94 of the inner shell and the inner shoulder of the middle shell. The outer shell or ring 90 has an upper inner shoulder 92, and this shell or ring is carried by the middle shell by spacing blocks 91 which cooperate with the upper inner shoulder of the outer ring or

shell and the lower outer shoulder 84 of the middle shell. This construction is clearly illustrated in Fig. 8A. If desired, the blocks for spacing the shells may be riveted or otherwise permanently secured to the shells, as illustrated in Figs. 9 and 9A, in order to enable ready assembly of the shaping element. If desired, however, they may be separate and loosely mounted between the shells. The spacing blocks supporting the innermost shell on the blow pipe are not attached to the contiguous shell but may be placed readily between the shoulder of the blow pipe and the upper inner shoulder of the innermost shell.

The shaping element 87 is short and, consequently, the heat-confining shell 85 may be correspondingly short. Within the shell 85 is located the adjustable shield 86 and is mounted and operated in a manner similar to that shown in Fig. 5. Also, the shell 85 may be adjusted with respect to the forebay 32 and the damper ring 88 may be varied in its position, as in the form shown in Fig. 5, to control the temperature produced by the flames of the burners 65 about the glass as it is formed into ware by the shaping element and control the viscosity of the glass and, thus, control the shape of the ware as finally produced.

In the form of shaping element 87, shown in Fig. 10, a refractory frustum member 88 is secured to the lower end of the blow pipe 47. The member 88 has a central bore and forms a refractory nozzle for the lower end of the blow pipe to deliver air to the interior of the glass as it is formed by the shaping element.

The member 88 of the shaping element is surrounded by a member 100 of refractory material and is substantially enclosed therein. The member 100 is, also, frustum in form and provided with an inner and upper shoulder 101 and the member 88 is provided with an outer and lower shoulder 102, and spacing blocks 104 are located intermediate the shoulders to support the member 100 on the member 88.

The shaping element may, also, be supported in the upper end of a heat-confining shell 85, like that shown in Fig. 8, and the shell 85 may be provided with the zonal temperature controlling parts, also shown in Fig. 8.

The glass-shaping element 87 is supported on the blow pipe at the lower terminus of the outlet 51 of the forebay 32 and the glass flows from the outlet over the top edges of the members 88 and 100 and over the outer sides of these parts and divides at and moves along the spacing blocks 104 coalescing at the ends of the spacing blocks within the member 100 and continues to move over the interior and exterior of the member 100 to form tubular glassware.

In the form of the construction shown in Fig. 11, the molten glass conduit tube, that forms the outlet 51 of the forebay 32, may be extended, or a tube, such as the tube 107, forming a continuation of the outlet 51, may be used to convey the glass to near the lower part of the shell 84. The glass-shaping element 105 may be located within the end of the molten glass conduit tube 107. The blow pipe 108, formed of refractory material, is located in the conduit tube 107. The upper end of the blow pipe is closed and the lower end extends into the shaping element. The upper end of the blow pipe communicates with a source of compressed air by tubes 109 and 110. The tubes 110 abut tubes 109 (Fig. 13) that extend crosswise the stream of molten glass and may be covered with refractory, diamond-shaped

blocks 108, that permit free movement of the glass past the blocks to cause it to first divide at an upper corner and then coalesce at the bottom corner of each block. Asbestos gaskets 113 and 113' seal the blocks 108 and the pipe 108 to prevent entrance of air into the molten glass. The tubes 110 are located within the metal sleeves 103 and are secured to a part of the frame 34 by means of the lug 115 and screw 116. Pressure screws 118 are threaded into the sleeves 103 to press against the tubes 110, which, in turn, operate, by pressure, to seal the gaskets 113 and 113'. The lower ends of the molten glass conduit tube and the blow pipe are provided with shoulders 111 and 111', respectively. The shaping element 105 may be provided with inner and outer shoulders 112 and 112', respectively located in opposed relation to the shoulders 111 and 111', and spacing blocks 114, of the form illustrated in Fig. 12, may be located between the shoulders to connect the lower ends of the molten glass conduit 107 and the blow pipe 108 and to support these parts. The glass moves through the tube 107 from the forebay to the glass-shaping element and through the heat-confining shell 84 that is heated by the burners 65. The shell is, also, provided with the shield 86 that may be adjustably located by the crank 74 operating through the rod 78 and the frame 67, as in the form of construction shown in Fig. 5.

In this embodiment the conduit 107, the blow pipe 108 and the shaping element 105 mounted between the two at the bottom of the conduit 107 are supported on the framework by means of the structure described above. The tubes 110, as stated, are located within the metal sleeves 103 which are secured to a part of the frame 34 by the lugs 115 and the screws 116. The sleeves 103 and the tubes 110 extend radially of the shell 84, and the inner ends of the tubes 110 support the conduit 107. The shaping element 105 and the blow pipe 108 are supported by the conduit 107 at the lower end thereof. Of course, some support for the blow pipe 108 is obtained at the upper end by virtue of the tubes 109 which extend into the blow pipe. When the structure is put together in the manner described above, radial pressures are exerted through the tube 110, the spacing blocks 108 and the gaskets 113 and 113' so that a part of the weight of the blow pipe is carried in this manner instead of through the shaping element to the lower end of the conduit 107.

The glass-shaping element 105 is formed with an outer lower end surface part sloping curvily toward the axis of the shaping element. This cooperates with the surface tension of the glass to cause the glass to move convergently. If desired, the inner surface may slope curvily away from the axis, as in the form shown in Fig. 14, to produce a tube of increased diameter. The structure shown in Fig. 14 is the same as that shown in Fig. 11 except for the shape of the lower end of the shaping element. The shaping element 105a has an inner shoulder 112a and an upper outer shoulder 112b similar to the shoulders 112 and 112' of the shaping element 105 shown in Fig. 11. These shoulders cooperate with spacing blocks 114, the inner block 114 abutting against the shoulder 111' on the blow pipe and the outer block abutting against the shoulder 111 on the conduit 107.

In the forms of shaping element shown in Figs. 15 and 16, a body part 117 is provided with inner 75 and outer shoulders 118 and the molten glass

conduit and the blow pipe are provided with shoulders 120 and 120', respectively located in opposed relation to the shoulders 118 to connect and support the parts relative to each other through the engagement of the spacing blocks 114. The body part 117 of the spacing element is provided with a plurality of recesses 122, each having a pin 124 embedded in the refractory material and extending across the recess and a replaceable glass-shaping tip 125 (Fig. 15) or 125' (Fig. 16), of any form, may be connected to the pins 124, by means of hooked wires 127 that have end parts embedded in the tips. Thus, glass-distributing or directing tips, of any form, may be connected to the body part of the element to modify the thickness of the tube wall and the delivery spread or area of distribution of the glass as it leaves the shaping element.

The form of glass-shaping element shown in Figs. 15 to 19 may be located in a heat-confining shell, which is, also, provided with a heat-intensifying shield and heat-regulating parts, shown in Figs. 5, 8, and 11, to control the viscosity of the glass as the ware is formed.

The shaping elements shown in Figs. 20 to 23, 25 inclusive, are formed of coaxially disposed, thin-walled metal shells. The metal shells 128 in Fig. 20, 128' in Fig. 21, and 128'' in Fig. 22 have extended skirt portions 130, 130' and 130'', respectively. The skirt portions extend below the supports for the shells and provide a plurality of passageways through which the glass flows for any desired distance, depending upon the lengths of the skirt portions, before the streams of glass passing between the elements are merged as the 35 glass leaves the shaping element. The plurality of skirts provides a means for causing accumulation of glass at a substantially common ware-forming point to cause a large, uniform, cross-sectional delivery of glass as the ware is formed so that ware having a thick wall may be produced or thin-walled ware may be more rapidly produced by an increase in the speed of draw.

Referring to Fig. 20, the shells 128 have inner shoulders 131 and outer shoulders 131a. The molten glass conduit 107 and the blow pipe 108 have shoulders 120 and 120a, respectively. Supporting and spacing blocks 114 are located between the shells and between the outer shell and the glass conduit and between the inner shell and the blow pipe for connecting the parts together and for supporting the shells and the blow pipe.

The skirts of the shaping elements may vary in length as between the inner and the outer shells to vary the glass distribution. In Fig. 21 the skirts 130' of the shells 128' progressively increase from the outer shell to the inner shell. If desired, they may vary in the reverse direction. Except for the difference between the shaping elements 128 and 128' of Figs. 20 and 21, respectively, the structures illustrated in these two figures are the same.

The structure illustrated in Fig. 22 is the same as the structure illustrated in Fig. 20 except that the shaping element has been modified to include a substantially spherical, broad refractory member 132. The bore of the member 132 is axially aligned with the bore of the blow pipe and is supported on the innermost of the shells 128''. The skirt 130'' of the inner shell is provided with strips 134, and the refractory member 132 has pins 135 embedded therein which project radially therefrom and engage the strips 134. The refractory member 132 is preferably contiguous

to the end of the blow pipe 108 but spaced sufficiently therefrom to permit movement of glass between the blow pipe and said body so that glass may flow downwardly interiorly of the member. The spherical outer surface tends to lead or draw the glass inwardly as it leaves the skirts of the shells 128'' to further reduce the diameter of the ware being formed.

I claim:

1. In apparatus for forming tubular glassware, a glass-shaping element comprising a plurality of coaxial shells, at least one of said shells having a pair of shoulders thereon, one of said shoulders being on the inside and the other on the outside of the shell, each of the remaining shells having at least one shoulder thereon, spacing and supporting blocks disposed between adjacent shells and arranged to engage adjacent shoulders, and means cooperating with a shoulder of one of said shells having inner and outer shoulders for supporting the element.

2. A glass-shaping element for use in apparatus for forming tubular glassware comprising a plurality of members positioned one within another and having their lower ends terminating substantially in a plane, said members having inter-engaging supporting means and providing a plurality of spaced coaxial openings at the point of discharge from the glass-shaping element through which the molten glass may pass to form the ware.

3. A glass-shaping element for use in apparatus for forming glassware comprising a plurality of members positioned one within another, one end of each member terminating in and, together with the adjacent end of each other member, forming a ware-forming plane, and supporting means extending radially of said members for maintaining them in fixed position with respect to each other, said members providing a plurality of radially spaced openings from which glass may be discharged as it leaves the shaping element.

4. A glass-shaping element for use in apparatus for forming tubular glassware comprising a plurality of members positioned one within another, adjacent ends of each member terminating in substantially the same plane, and radially extending supporting means for supporting the members in fixed position with respect to each other, said members providing a plurality of spaced openings at the point of discharge from the glass-shaping element through which the molten glass may pass to form the ware.

5. A glass-shaping element for use in apparatus for forming tubular glassware comprising a plurality of members positioned one within another, one end of each member terminating in and, together with the adjacent end of each other member, forming a ware-forming plane, and radially extending supporting means extending between said members, said supporting means being relatively smaller than the spaces between said members, said members providing a plurality of radially spaced openings from which glass may be discharged as it leaves the shaping element.

6. A glass-shaping element for use in apparatus for forming glassware comprising a plurality of members positioned one within another, one end of each member terminating in and, together with the adjacent end of each other member, forming a ware-forming plane, supporting means extending radially of said members for maintaining them in fixed position with respect to each other, said members providing a plu-

6
rality of radially spaced openings from which glass may be discharged as it leaves the shaping element, and means on the members adjacent the point of discharge for retarding glass flow downwardly between the members and for producing glass accumulation therebetween.

7. A glass-shaping element for use in apparatus for forming glassware comprising a plurality of spaced shells positioned one within another, the wall thickness of each of said shells being appreciably smaller than the length thereof, one end of each shell terminating in and, together with the adjacent end of each other shell, forming a ware-forming plane, and supporting means extending radially of said shells for maintaining them in fixed position with respect to each other, said shells providing a plurality of radially spaced openings from which glass may be discharged as it leaves the shaping element.

8. In apparatus for forming hollow glassware, a source of molten glass, means for forming a tubular stream of molten glass, a glass-shaping element comprising a plurality of members positioned one within another, one end of each member terminating in and, together with the adjacent end of each other member, forming a ware-forming plane, said members forming a plurality of radially spaced openings through which molten glass may pass as it is discharged from the shaping element, and means for supporting the glass-shaping element on said glass stream forming means.

9. In apparatus for forming hollow glassware, means for forming a tubular stream of molten glass, a glass-shaping element, and supporting means for supporting the shaping element in the path of said tubular stream of molten glass, said glass-shaping element comprising a plurality of members positioned one within another, one end of each member terminating in and, together with the adjacent end of each other member, forming a ware-forming plane, said members providing a plurality of radially spaced openings at the point of discharge from the glass-shaping element through which the molten glass may pass to form the ware.

10. In apparatus for forming hollow glassware, a glass-shaping element in combination with a glass discharge conduit, said element comprising a plurality of members positioned one within another coaxially with the conduit and having their lower ends terminating substantially in a ware-forming plane, said members having inter-engaging supporting means and providing a plurality of spaced coaxial openings at the point of discharge from the glass-shaping element through which the molten glass may pass to form the ware.

11. In apparatus for forming tubular glassware, a glass discharge conduit, a glass-shaping element comprising a plurality of members positioned one within another coaxially with the conduit and having their lower ends terminating substantially in the same plane, said members having radially extending supporting means and providing a plurality of spaced coaxial openings at the point of discharge from the glass-shaping element through which the molten glass may pass to form the ware.

12. In apparatus for forming hollow glassware, a source of molten glass, means for forming a tubular stream of molten glass, a glass-shaping element comprising a plurality of members positioned one within another, one end of each member terminating in and, together with the ad-

5
jacent end of each other member, forming a ware-forming plane, said members forming a plurality of radially spaced openings through which molten glass may pass as it is discharged from the shaping element, radially extending means for supporting one of said members in the tubular stream of molten glass, and means extending radially between said member and the other members for supporting the last-mentioned members on the first-mentioned member.

13. In apparatus for forming hollow glassware, a source of molten glass, means for forming a tubular stream of molten glass, a glass-shaping element comprising a plurality of members positioned one within another, one end of each member terminating in and, together with the adjacent end of each other member, forming a ware-forming plane, said members forming a plurality of radially spaced openings through which molten glass may pass as it is discharged from the shaping element, radially extending means for supporting one of said members in the tubular stream of molten glass, and means extending radially between said member and the other members for supporting the last-mentioned members on the first-mentioned member, each of said members having a skirt portion extending below its point of support, whereby the glass may flow around and between said members uninterrupted and unite to form single walled tubular ware as it is discharged from the shaping element.

14. In apparatus for forming hollow glassware, means for forming a tubular stream of molten glass, a glass-shaping element, supporting means for supporting the shaping element in the path of said tubular stream of molten glass, said glass-shaping element comprising a plurality of members positioned one within another, one end of each member terminating in and, together with the adjacent end of each other member, forming a ware-forming plane, said members providing a plurality of radially spaced openings and separating the stream of glass into a plurality of streams which are thereafter merged together at the ware-forming plane as the glass is discharged from the shaping element, and means for supporting the glass-shaping element on said glass stream forming means.

15. In apparatus for forming hollow glassware, a source of molten glass, means for forming a tubular stream of molten glass, a glass-shaping element comprising a plurality of members positioned one within another, one end of each member terminating in and, together with the adjacent end of each other member, forming a ware-forming plane, said members forming a plurality of radially spaced openings through which molten glass may pass as it is discharged from the shaping element, a blow pipe extending to a point within the innermost member, radially extending means supporting the innermost member on the blow pipe, and radially extending means between the innermost member and the other members for supporting all said other members on the innermost member.

16. In apparatus for forming hollow glassware, a source of molten glass, means including a conduit and a blow pipe for forming a tubular stream of molten glass, a glass-shaping element comprising a plurality of members positioned one within another, one end of each member terminating in and, together with the adjacent end of each other member, forming a ware-forming plane, said members forming a plurality of radially spaced openings through which molten glass may pass as it is discharged from the shaping element, a blow pipe extending to a point within the innermost member, radially extending means supporting the innermost member on the blow pipe, and radially extending means between the innermost member and the other members for supporting all said other members on the innermost member.

ally spaced openings through which molten glass may pass as it is discharged from the shaping element, and means for supporting the blow pipe and the glass-shaping element on said conduit.

17. In apparatus for forming hollow glassware, a source of molten glass, means including a conduit for receiving molten glass from said source and for forming a tubular stream of molten glass, a glass-shaping element comprising a plurality of members positioned one within another, one end 10 of each member terminating in and, together with the adjacent end of each other member, forming a ware-forming plane, said members forming a plurality of radially spaced openings through which molten glass may pass as it is discharged from the shaping element, and means for supporting the glass-shaping element on said glass stream forming means.

18. In apparatus for forming hollow glassware,

means for forming a tubular stream of molten glass, a glass-shaping element, supporting means for supporting the shaping element in the path of said tubular stream of molten glass, said glass-shaping element comprising a plurality of members positioned one within another, one end of each member terminating in and, together with the adjacent end of each other member, forming a ware-forming plane, said members providing a plurality of radially spaced openings at the point of discharge from the glass-shaping element through which the molten glass may pass to form the ware, and means carried by the members adjacent the point of discharge for retarding the glass flow downwardly between the members and for producing glass accumulation therebetween.

EDWARD DANNER.
